UNITED STATES PATENT OFFICE

156,445

MOTOR COACH

Raymond Loewy, New York, N. Y., assignor to
 The Greyhound Corporation, Chicago, Ill., a corporation of Delaware

Application December 29, 1948, Serial No. 150,423

Term of patent 14 years

(Cl. D14—3)

To all whom it may concern:

Be it known that I, Raymond Loewy, a citizen of the United States, residing at New York, in the county of New York and State of New York, have invented a new, original, and ornamental Design for a Motor Coach, of which the following is a specification, reference being had to the accompanying drawing, forming part thereof, and in which

Fig. 1 is a perspective view showing one side and part of the front of a motor coach, embodying my design;

Fig. 2 is a view similar to Fig. 1 showing the other side of the coach;

Fig. 3 is a front elevational view; and
 Fig. 4 is a rear elevational view.

I claim:
 The ornamental design for a motor coach, substantially as shown.

RAYMOND LOEWY.
